(57) **CLAIM**

We claim the ornamental design for food product, as shown.

DESCRIPTION

FIG. 1 is a perspective view of a food product, according to the present invention;

FIG. 2 is a left side view of the food product of FIG. 1;

FIG. 3 is a right side view of the food product of FIG. 1;

FIG. 4 is a top plan view of the food product of FIG. 1;

FIG. 5 is a bottom plan view of the food product of FIG. 1;

FIG. 6 is a top end view of the food product of FIG. 1; and,

FIG. 7 is a bottom end view of the food product of FIG. 1.
